UNITED STATES PATENT OFFICE.

EDWARD S. STIMPSON, OF HOPEDALE, MASSACHUSETTS, ASSIGNOR TO DRAPER COMPANY, OF HOPEDALE, MASSACHUSETTS, A CORPORATION OF MAINE.

LOOM-SHUTTLE.

1,117,719.

Specification of Letters Patent. Patented Nov. 17, 1914.

Application filed August 4, 1913. Serial No. 782,872.

To all whom it may concern:

Be it known that I, EDWARD S. STIMPSON, of Hopedale, in the county of Worcester and State of Massachusetts, have invented 5 certain new and useful Improvements in Loom-Shuttles, of which the following is a specification.

The present invention relates to an automatically threading shuttle having a slotted eye and adapted to be used in a weft replenishing loom, and the present improvements relate to a metallic lining for the eye and to a combined thread guide and guard which directs the thread into the eye and 15 prevents the escape of the thread therefrom.

The improvements are illustrated in the accompanying drawings in which—

Figure 1 is a plan view of the eye end of the shuttle. Fig. 2 is a horizontal section 20 in the plane indicated by the line 2—2 in Fig. 4. Fig. 3 is a longitudinal section of the body of the shuttle in the plane indicated by the line 3—3 in Fig. 2, the eye lining and combined thread guide and guard 25 being in elevation, and a portion of the thresher being broken away. Fig. 4 is a cross section in the plane indicated by the line 4—4 in Fig. 3. Fig. 5 is a perspective view of the eye lining and the combined 30 thread guide and guard detached.

The improvements are shown as applied to an automatically threading shuttle which is substantially similar to that shown in United States Letters Patent, No. 933,497, 35 September 7, 1909. The shuttle A has a threading chamber B at its eye end in which is located a sheet metal thresher. As in that patent, this sheet metal thresher comprises separated vertical side walls, C. 40 D, with a thread passage I between them, a beak E at the outer end which overhangs the outer end of the thread passage and directs the thread to the slotted eye F. of the shuttle, a guard G at the front which overhangs the beak E, and a guard H at the inner end of the thread passage which retains the thread in the thread passage between the two side walls of the thresher. The wall C is at the eye side or front of 45 the shuttle and the wall D is at the opposite or rear side. The thresher is held in place by means of a transverse bolt J, which extends through apertures in the shuttle body and in the walls of the thresher, this bolt 50 screwing into a nut K, counter-sunk in the rear side of the shuttle body, as shown in

Fig. 2. In all of these respects the construction is substantially as shown in Patent No. 933,497. The present improvements are especially adapted for use with a 60 shuttle having the thresher of said Patent No. 933,497. The improved eye lining, together with the improved thread guide and guard are formed from a single piece of sheet metal as illustrated in Fig. 5. The eye 65 lining comprises a cylindrical tube L open at its top and both ends and having two upwardly projecting and separated tongues M and N. The outer tongue M seats against the wood of the shuttle body at the outer 70 side of the eye slot as shown in Fig. 2, while the tongue N seats against the wood of the shuttle body at the opposite or inner side of the eye slot. The cylindrical tubular lining L rests upon the bottom of the eye slot. The 75 combined thread guide and guard O is made in one piece with the eye lining and it extends from its lower end where it joins the tube L outwardly toward the point of the shuttle and forwardly toward the front wall 80 of the shuttle. The extreme upper end of the thread guide O extends close up to the top P of the thresher and behind the beak E and above the lower edge of the beak. Accordingly, the thread cannot possibly pass 85 over the top of the thread guide O nor can it get caught between the thread guide O and the front wall C of the thresher. Immediately after a fresh bobbin has been inserted into the shuttle, the shuttle travels 90 inwardly with the eye end back. As the free end of the bobbin or cop thread is attached (in the manner common in the well-known Northrop loom) the thread is laid in the thread passage I below the beak E in a well-known way. Then, when the shuttle travels 95 in the opposite direction with its eye end forward, the thread (which is then held by the cloth) rides down the thread guide O and is guided thereby over the top of the 100 outer tongue M and into the cylindrical lining L of the shuttle eye. Thereafter, the thread travels through the thread passage I out through the cylindrical lining and draws against the base of the thread guide O as 105 shown in Fig. 2, and against either the outer or the inner portion of the metallic lining depending upon the direction in which the shuttle is traveling. No special snubbing posts are employed; the eye lining and its 110 adjuncts serving the purpose.

It is of vital importance that the thread

should not escape from the eye during the running of the shuttle. This is prevented by two expedients in addition to the obstruction to the escape of the thread afforded by 5 the threader itself. The thread guide O extends close to the body of the shuttle outwardly beyond the eye, thus affording a narrow throat Q (see Fig. 2) just wide enough for the passage of the thread. This narrow 10 throat is located at the plane in which the section shown in Fig. 2 is located. Below the plane of this throat, as shown by the section line 2—2 in Fig. 4, the thread guide O is provided with a downwardly and rearwardly extending catch R which is below the 15 plane of the throat Q and which extends partly across the thread passage so as to act as a guard to obstruct any upward throw of the thread as high as the throat. Accordingly, 20 the thread is effectively retained within the thread eye, thus preventing breakage of the thread which is a frequent incident of its escape from the eye.

The forward tongue M is not as high as 25 the rear tongue N, as shown in Figs. 3, 4 and 5 of the drawings. Accordingly, the entering thread passes over the top of the front tongue M and the rear tongue N prevents the thread from coming in contact with the 30 wood of the shuttle at the inner side of the eye slot.

I claim:

1. An automatically threading shuttle having, in combination, a sheet metal 35 threader having a thread passage and an overhanging beak at the outer end of the thread passage; a slotted eye; a sheet metal cylindrical lining for the eye open at both ends and at the top with integral upwardly 40 extending tongues lying against the outer and inner sides of the eye slot, the outer tongue being shorter than the inner tongue; a combined thread guide and guard integral with the lining, and extending from the inner rear portion of the lining upwardly, outwardly and forwardly and approaching a portion of the shuttle outwardly beyond the eye so as to leave a narrow throat for the passage of the thread; and a rearwardly and downwardly extending catch integral with the guide and located below the 45 throat.

55 2. An automatically threading shuttle having, in combination, a thread passage and an overhanging beak at the outer end of the thread passage; a slotted eye; a metallic cylindrical lining for the eye open at both ends and at the top with integral upwardly 60 extending tongues lying against the outer and inner sides of the eye slot, the outer tongue being shorter than the inner tongue; a combined thread guide and guard

integral with the lining, and extending from the inner rear portion of the lining upwardly, outwardly and forwardly and approaching a portion of the shuttle outwardly beyond the eye so as to leave a narrow throat for the passage of the thread, 70 the upper end of the guide extending behind the beak and above the lower edge thereof; and a rearwardly and downwardly extending catch integral with the guide and located below the throat.

75

3. An automatically threading shuttle having, in combination, a thread passage and an overhanging beak at the outer end of the thread passage; a slotted eye; a metallic lining for the eye open at both ends 80 and at the top with integral upwardly extending tongues lying against the outer and inner sides of the eye slot, the outer tongue being shorter than the inner tongue; a combined thread guide and guard integral with the lining, and extending from the inner rear portion of the lining upwardly, outwardly and forwardly and approaching a portion of the shuttle outwardly beyond the eye so as to leave a narrow throat for the 85 passage of the thread; and a rearwardly and downwardly extending catch integral with the guide and located below the throat.

80

4. An automatically threading shuttle having, in combination, a thread passage; a slotted eye; and a metallic cylindrical lining for the eye open at both ends and at the top; and a combined thread guide and guard integral with the lining, and extending from the inner rear portion of the lining upwardly, outwardly and forwardly and approaching a portion of the shuttle outwardly beyond the eye so as to leave a narrow throat for the passage of the thread; and a rearwardly and downwardly extending catch integral with the guide and located below the throat.

95

5. An automatically threading shuttle having, in combination, a thread passage; a slotted eye; a lining for the eye open at both ends and at the top; a thread guide extending from the inner rear portion of the lining upwardly, outwardly and forwardly and approaching a portion of the shuttle outwardly beyond the eye so as to leave a narrow throat for the passage of the thread; and a catch extending rearwardly and downwardly from the guide partly across the thread passage and located below the throat.

100

6. An automatically threading shuttle having, in combination, a thread passage; a slotted eye; a lining for the eye open at both ends and at the top; a thread guide extending from the inner rear portion of the lining upwardly, outwardly and forwardly and approaching a portion of the shuttle outwardly beyond the eye so as to leave a 115

110

120

narrow throat for the passage of the thread; and a catch extending rearwardly from the guide partly across the thread passage.

7. An automatically threading shuttle having, in combination, a threader having a thread passage and an overhanging beak at the outer end of the thread passage; a slotted eye; a thread guide extending from the inner rear portion of the eye upwardly, outwardly and forwardly and approaching a portion of the shuttle outwardly beyond the eye so as to leave a narrow throat for the passage of the thread, the upper end

of the guide extending close to the top of its threader and behind the beak; and a ¹⁵ catch extending rearwardly from the guide partly across the thread passage and located below the throat.

In witness whereof, I have hereunto signed my name in the presence of two sub- ²⁰ scribing witnesses.

EDWARD S. STIMPSON.
